JOHN D. MURRAY, OF SAN FRANCISCO, CALIFORNIA

TIP FOR SPRAYING NOZZLES

Application filed May 31, 1927. Serial No. 195,281.

This invention relates to improvements in tips for nozzles such as employed to discharge and apply liquids under pressure, as for example in the art of discharging and applying paints, varnishes, lacquers, oils, germicidal liquids and the like, under the commonly called air brush painting or spray gun painting methods.

An object of my invention is to provide a nozzle tip which will discharge liquids under pressure in a fan-shaped flat, film-like sheet without waste of the liquid and without the danger and annoyance to operators such as usually caused by the present day tips, due to their scattering a great part of the sprayed material into the atmosphere as an atomized vapor.

A further object is to provide a nozzle tip which is adaptable to the discharging of liquids under pressure in the manner technically called "flowing" and also in the manner called "atomizing"; a further object also being to provide a nozzle tip which is inexpensive to manufacture and which may be easily made adaptable to use with any nozzle for discharging liquids under pressure from any suitable pressure source.

A further object of this invention is to provide a nozzle tip of the character described which will cause the liquid to be evenly distributed throughout the entire area of the fan-like sheet discharged from the tip, thereby providing for a smooth and even application, and preventing waste of the liquid.

With the above mentioned and other objects in view, the invention consists of the novel construction hereinafter described, illustrated in the accompanying drawing, and set forth in the claims hereto appended, it being understood that various changes in form, proportion, size and minor details of construction within the scope of the claims may be resorted to without departing from the spirit or sacrificing any of the advantages of the invention.

Referring to the drawing:

Fig. 1 is a cross section on the center line of the tip as it appears attached to a liquid pressure line, when the transverse slot of the tip is horizontally disposed.

Fig. 2 is a side elevation of the same position of the tip, as shown in Fig. 1.

Fig. 3 is a top plan view.

Fig. 4 is a cross section on line 4—4 of Fig. 3, showing one angle at which the ends of the slot may be stopped.

Fig. 5 is a cross section on the line 4—4 of Fig. 3, showing a modification of the angle at which the ends of the slot may be stopped.

Figs. 6 and 7 are longitudinal sections of modified forms.

More fully described in conjunction with the drawing, the tip in the one form of my invention, may be said to consist of a dome-like structure generally designated 1, which is provided with a transverse slot or orifice 2, said slot passing through the apex and extending down the sides of the dome to the small annular shoulder 3, the opposite faces of said slot being parallel; said annular shoulder 3 serving to prevent backlash. A second annular shoulder 4 is provided adjacent the open end of the tip, which end is opposite the dome 1, this second shoulder 4 being adapted to engage the inwardly extending flange 5 of a collar generally designated 6, which collar is equipped with threads 7 adapted to engage similar threads on a feed pipe 8. Pipe 8 leads from a source of liquid, not shown, said liquid being under pressure when the tip is being used to discharge liquids. An annular recess 9 is cut in the end of the pipe 8 and receives the inner end 10 of the tip. This structure provides a leak proof seat and a smooth joint, so that the inside bore of the tip is substantially a continuation of the bore of the pipe 8.

The dome is so constructed that the thickness thereof where the orifice 2 passes through it, is greatest at the apex 11 and tapers away in equal degrees of gradation in each direction towards the ends of the orifice. My preferred form of dome has both the outer wall and the inner wall conforming to the surface of a sphere of the same diameter, so that said outer and inner walls of the dome are of the same degree of curvature; thus the transverse slot is formed with identical opposing kerf-walls having defining edges in register in the same plane, and

having the inner and outward edges respectively defined by lines of the same degree of curvature struck from spaced points on the same axial line in direction of flow through the kerf, said curves being preferably arcs of circles, as best shown in Figs. 4 and 5. Where the ends of the kerf are referred to, they are called "end walls" to distinguish from the walls or resistance-producing faces 10 of the kerf. The oppositely disposed ends of the slot 2 are stopped as at 12 at an angle less than ninety degrees to the longitudinal axis of the tip, said angle being in the direction of the line of liquid flow, Fig. 4. The 15 opposing ends of the slot may each be stopped on curved lines 13 which occupy about the same relation with respect to the longitudinal axis of the tip as the angles 12 bear to its slot, (Figure 4).

20 Fig. 6 shows a section of a dome, the inner and outer surfaces of which are formed by curves that are not arcs of circles. Since it is possible to form a dome from various types of curves, I do not wish to confine myself to 25 any set series of curves. It is further manifest that equivalent constructions may be used in place of a transversely slotted dome, such for instance as a transversely slotted conical structure such as shown in Fig. 7.

30 In operation, the liquid material to be discharged under pressure is conducted to the tip by the conduit or pipe 8, thence passing into the chamber 14 of the tip, and is discharged through the orifice 2 of the dome 1. Due to 35 the centrifugal action of the liquid under compression and to the tendency of the liquid to follow the line of least resistance, the parallelly disposed faces of the slot 2 are purposely made of greater thickness at the apex 11 than 40 at their ends. The tapering of the width of the faces or walls of the slot 2 from the point 11 to the shoulders 3, graduates the resistance to the flow of material, so that at all points on the surface of the faces of the slot the resistance 45 created to the flow of material is substantially equal. It is obvious from the shape of the transverse slot that the discharge of the liquid will be in a flat film form. To provide this fan-shaped form and to prevent the liquid 50 discharging at right angles to the longitudinal axis of the tip, at the shoulders 3, the ends of the slot in the tip are terminated angularly as hereinbefore described, and as shown in the drawing at 12 and 13. By this arrangement 55 the liquid is evenly distributed throughout the entire area of the fan-like jet. Shoulders 3 serve to prevent backlash of the liquid being discharged.

In the use of my invention, the width of the 60 fan-shaped jet is determined by the amount of the pressure used to discharge the liquid; the greater the pressure, the wider the spread of the fan-shaped jet. The adaptation of the tip to either flowing or atomizing is regulated by 65 the manner of application of the pressure. In

"flowing" the pressure is placed behind the material only, whereas in "atomization" an auxiliary pressure is injected into the liquid to break it up into small particles prior to its passage through the orifice of discharge.

I have provided in the construction of my invention a tip for nozzles adapted to the "flowing" of liquid materials without atomization, or to the discharge of atomized liquid materials if desired, and which will apply the liquids to the surfaces to be covered in either a broad or narrow jet, may be attached to various types of spraying nozzles, and having a universality of use, such as in paint spraying, orchard spraying, oil burning, or, in fact, any use where a fluid stream under pressure is desired to be discharged in flat film form.

I wish it to be understood that any nozzle tip which provides for discharging liquid under pressure from a discharge orifice which is formed to create greater resistance to the discharge of liquid therethrough at a point between the ends of the orifice, but diminishes the resistance to the discharge of the liquid in equal degrees in each direction from said point to the ends of said orifice, regardless of shape, size and formation thereof, comes under the scope and spirit of my invention as defined in the accompanying claims.

Having thus described my invention, I claim:

1. A tip for discharging fluids under pressure formed in the shape of a dome provided with a discharge slot, the walls of said slot having defining edges in register and being of maximum width at the center and diminishing in width in the same degree of gradation in each direction therefrom, said slot terminating in end walls that form an angle of less than ninety degrees with the longitudinal axis of the tip, in the direction of the flow of liquid.

2. A tip for discharging liquids under pressure formed in the shape of a dome provided with a transverse discharge slot, the transverse walls of said slot being of maximum width at the center and diminishing in width in the same degree of gradation in each direction therefrom, said slot terminating in curved end walls having curvature of less than ninety degrees angle with the longitudinal axis of the tip, in the direction of the flow of liquid, the surfaces of said transverse walls being characterized by identity of definition.

3. Means for equalizing the resistance to the flow of fluid material from a nozzle and for causing the material to be discharged in a flat film form of fan contour, comprising a tip structure having a kerf whose walls are in relative parallelism and formed with surfaces which are graduated in width equally in each direction from a portion of maximum width, and being of the same width at oppositely disposed portions thereon.

4. Means for equalizing the resistance to

the flow of liquid material from a nozzle and for causing the material to be discharged in a flat film form of fan contour, comprising a dome-shaped tip structure having an axial kerf whose walls are in relative parallelism and formed with surfaces which are graduated in width and arranged with portions of maximum width at the immediate longitudinal axis of the structure.

5. Means for equalizing the resistance to the flow of liquid material from a nozzle and for causing the material to be discharged in a flat film form of fan contour, comprising a dome-shaped tip structure having an axial kerf whose walls are in relative parallelism and formed with surfaces which are graduated in width and arranged with portions of maximum width at the immediate longitudinal axis of the structure and with portions of diminishing width respectively extending in opposite directions from the portions of maximum widths.

6. Means for equalizing the resistance to the flow of liquid material from a nozzle and for causing the material to be discharged in flat film form of fan contour, comprising a dome-shaped tip structure having an axial kerf whose walls are in relative parallelism and formed with surfaces which are graduated in width and arranged with portions of maximum width at the immediate longitudinal axis of the structure and with portions of diminishing width respectively extending in opposite directions from the portions of maximum widths, the ends of the kerf formed of end walls extending forwardly and outwardly.

7. A nozzle tip having a body portion, a kerf through said body portion, said kerf having opposing walls in relative parallelism, the respective inner and outer edges of each of said walls being defined by the same degree of curvature.

8. A dome shaped nozzle tip, having a kerfed body portion, said kerf having opposing walls with defining edges in register, the respective outer and inner edges of each of said walls being defined by the same degree of curvature.

9. A nozzle tip comprising a dome-shaped body portion, the respective inner and outer surfaces of said dome being formed with equal degrees of curvature, a kerf in said dome connecting the inner and outer surfaces thereof, each of the opposing walls of said kerf having a portion of maximum width intermediate the ends thereof and being decreased in width in each direction equally from said portion of maximum width to the respective ends of the kerf.

10. A nozzle tip having a kerfed body portion, said kerf having opposing walls in relative parallelism, the respective outer and inner edges of each of said walls being defined by segments of a circle struck with equal

radii from spaced points on the axial line of the kerf taken in direction of flow through the kerf.

11. A nozzle tip having a body portion, a kerf through said body portion, each of the opposing walls of said kerf being characterized by identity of definition and formed with wall surface graduated in width equally in each direction from a portion of the maximum width, the ends of said kerf being formed with end walls which extend forwardly and outwardly.

12. A tip for discharging fluids under pressure, which tip is provided with a discharge orifice having oppositely disposed walls, means to create maximum resistance to the discharge of fluids through said orifice at a portion thereof between the ends of the orifice, and means to diminish the resistance to the discharge of the fluid in equal degrees in each direction from said portion of maximum resistance to the ends of said orifice, the opposed surfaces of said oppositely disposed walls of the discharge orifice being characterized by identity.
